UNITED STATES PATENT OFFICE.

NEWEL AUSTIN JENNET, OF RANGER, TEXAS.

ELEVATOR FOR SUCKER RODS.

Application filed November 14, 1921. Serial No. 515,008.

To all whom it may concern:

Be it known that I, NEWEL AUSTIN JENNET, a citizen of the United States, and a resident of Ranger, in the county of Eastland and State of Texas, have invented a new and useful Improvement in Elevators for Sucker Rods, of which the following is a full, clear, and exact description.

My invention relates to devices for use in handling tubes and sucker rods in deep wells and it consists in the combinations, constructions and arrangements herein described and claimed.

An object of my invention is to provide a device of the character described which can be readily adjusted to a sucker rod to support the latter in a desired position.

A further object of my invention is to provide a device of the character described that has means adapted to engage a sucker rod or the like to prevent rotation of the sucker rod.

A further object of my invention is to provide a device of the character described that has co-acting means for locking the device in an adjusted position with respect to a sucker rod or the like, whereby accidental displacement of the sucker rod is precluded.

A further object of my invention is to provide a device of the character described that is strong and durable and at the same time is of a minimum weight for being capable of performing the service for which designed.

Other objects and advantages will appear in the following specification, and the novel features of the invention will be particularly pointed out in the appended claims.

My invention is illustrated in the accompanying drawings, forming part of this application, in which

Fig. 1 is a side elevation of a portion of the device and of a portion of a sucker rod engaged thereby,

Fig. 2 is a view similar to Fig. 1 showing the side of the device reverse to that illustrated in Fig. 1,

Fig. 3 is a plan view of a portion of the device,

Fig. 4 is a section along the line 4—4 of Fig. 3, and

Fig. 5 is a bottom plan view of a portion of the device.

In carrying out my invention, I provide a carrying frame 1, which in the form of the device illustrated, consists of a block pro-

vided with a bore 2 and with a counter bore 3 at the upper end thereof. The block 1 has integral trunnions 4 which are axially aligned and extend at right angles to the axis of the bore 2. The axis of the bore 2 intersects the common axis of the trunnions 4, whereby the block 1 will normally be balanced when suspended between the arms of a bail 5, said arms being formed with integral hub portions at their extremities provided with bores 6 mounted on the trunnions 4.

The block 1 is formed with a transverse bore 7 leading from the outer wall thereof into the counter bore 3. A rotatable holding and retaining member is disposed in the counter bore 3 and in the form of the device illustrated embodies a circular disk 8 having formed therein a slot 9 extending from the outer wall beyond the center of the disk, as best seen in Figures 3 and 5. A retaining plate 10 is secured to the block 1 in countersunk relation to the upper surface thereof by screws 11 or like fastening means and prevents the displacement of the holding and retaining member without preventing the rotation of the latter. The disk 8 has an integral extension 12, which depends within the bore 2 and has arcuate inner and outer walls, thereby defining a slot 13 between the end walls of the extension, which slot is of greater extent than the distance between the corresponding points on opposite walls of the slot 9. It is to be observed at this point that the inner diameter of the extension 12 is greater than the distance between opposite points on the side walls of the slot 9, whereby portions of the disk 8, indicated at 14, 15 and 16 in the drawings, project into the bore of the extension 12. It

is to be observed also that the portions 14, 15 and 16 of the disks 8 project inwardly beyond the walls of a slot 17 in the cover plate 10 (see Fig. 3).

The transverse bore 7 is enlarged and threaded at 18 for engagement with a nipple portion 19 of a sleeve 20. The latter is formed with a bore 21 in which is slidably disposed a locking pin or plunger 22. The bore 21 is diametrically smaller at its outer end than the bore 7 and is enlarged intermediately to define an annular shoulder 23 which provides a seat for an expansion spring 24. The latter is disposed on the pin or plunger 22 and re-acts at its inner end against a collar 25, which is rigidly secured on the pin or plunger and is arranged

for slidable movement along the bore 7 and along the enlarged portion of the bore 21.

The disk 8 has formed therein radially extending bores 26 and 27, respectively. These 5 bores are positioned at right angles to one another and each is adapted to receive the inner portion of the locking pin or plunger 22. The latter will normally be moved into engagement with one of the bores 26 and 27

10 on account of the action of the spring 24. It will be apparent that the rotatable holding and retaining member will be maintained in such a position with respect to the carrying block that the slots through the 15 walls of the several parts described in the foregoing will be substantially alined, as illustrated in Fig. 3, when the locking plunger 22 projects into the bore 27. However, when the rotatable holding and retaining 20 member has been turned relatively to the block 1 so that the bore 26 is engaged by the locking pin or plunger 22, the web portions of the disk 8 and of the extension 12 will be positioned to extend across the slot 25 through the walls of the block 1 and in consequence a member moved into the slot 9 and extending beyond the ends of the block 1 will be confined within the holding and retaining member.

30 In order that the positioning of the holding and retaining member may be effected readily with entire accuracy, I provide a guide pin 28, which is preferably a screw or bolt threaded transversely through the 35 block 1 and projecting into a groove 29 in the outer wall of the disk 8. Portions of the walls of the groove 29 have integral portions indicated at 30 and 31, respectively, which protrude into the groove and serve as stop 40 members for limiting the movement of the rotatable disk 8 with respect to the guide pin 28. When the latter is in contact with the stop member 30, the bore 27 is in position to receive a portion of the locking pin 45 or plunger 22 and when the stop member 31 is in contact with the pin 28, the bore 26 is in the position formerly occupied by the bore 27.

When it is desired to withdraw the locking pin or plunger from either the bore 26 or the bore 27, a handle 32, which is secured to the pin 22 by a cotter pin 33 or like fastening means is turned about its axis. It will be observed that the outer wall of the 55 sleeve 20 is reduced along an oblique line to provide an annular cam surface indicated at 34. The handle 32 has an integral tubular portion 35 rotatably mounted on the reduced portion of the sleeve 20 and having 60 a beveled end wall adapted to co-act with the cam surface 34. When the tubular portion of the handle 32 is positioned in contact with the cam surface 34, as illustrated in Fig. 4, the action of the spring 24 moves 65 the locking pin or plunger into engagement

with either the bore 26 or the bore 27. When the handle 32 is rotated about its axis, the handle 32 will be moved outwardly on account of the engagement of the end wall of the tubular portion 35 with the cam 70 surface 34, thereby occasioning the withdrawal of the plunger 22 from the transverse bore of the disk 8 against the action of the spring 24.

From the foregoing description of the various parts of the device, the operation thereof may be readily understood. The device is designed particularly for use with sucker rods which are lowered into deep wells. In Fig. 1, I show a sucker rod, denoted by 75 the numeral 36. This sucker rod has the usual non-circular portion 37 below an external enlargement 38 and above another external enlargement 39. In the present embodiment of the invention, the recess or slot 80 9 through the disk 8 is non-circular and is adapted to the non-circular portion 37 of the sucker rod. The enlargement 38 of the latter will rest upon the portions 14, 15 and 16 of the disk 8 which protrude inwardly beyond the inner wall of the extension 12. The extension 12 will fit over the enlarged portion 39 of the sucker rod. Since the non-circular portion 37 of the sucker rod is engaged by the slot 9 of the disk 8, it will be 85 obvious that the sucker rod will be held within the slot 9 when the handle 32 has been manipulated to cause the retraction of the locking plunger 22 from the bore 27 and the carrying block 1 has been rotated relatively to the disk 8 until the bore 26 is in position to receive the locking pin or plunger 22. When the handle 32 is released, the locking pin or plunger 22 will engage the bore 90 and the sucker rod 36 will then be held against rotation and against longitudinal movement relative to the holding and retaining member. It will be understood that a cable (not shown) will be attached to the bail 8 and consequently the device can be 95 raised at will from a position in a deep well. 100

One of the advantages of the device is derived from the fact that the sucker rod is held against rotation relatively to the device and the latter therefore serves as a 115 wrench engaging with one length of the sucker rod when it is desired to connect or disconnect the retained length of the sucker rod with or from adjacent lengths.

I claim:

1. A device of the character described comprising a carrying block provided with a bore and having a slot extending from the outer wall of the block to said bore, a rod-engaging member carried by said block and having a slot arranged to register with the slot in the carrying member, whereby a rod can enter the slot in said rod-engaging member; said carrying member being rotatable with respect 125 to the carrying block.

to the rod-engaging member, whereby the rod is prevented by said carrying block from displacement out of the slot in said rod-engaging member.

- 5 2. A device of the character described comprising a carrying block provided with a bore and having a slot extending from the outer wall of the block to said bore, a rod engaging member carried by said block and 10 having a slot arranged to register with the slot in the carrying member, whereby a rod can enter the slot in said rod engaging member, said carrying member being rotatable with respect to the rod engaging member, 15 whereby the rod is prevented by said carrying block from displacement out of the slot in said rod engaging member, and means for locking the carrying block to said rod engaging member in the position to permit 20 entrance of the rod, and in the position to prevent the displacement of the rod.

- 3. A device of the character described comprising a carrying block provided with a bore and with a counterbore at one end, 25 said carrying block being formed with a slot extending transversely from the outer wall thereof to the bore and longitudinally for the entire length of the block, said slot having a width greater than the diameter of 30 a rod to be engaged, and a rotatable holding and retaining member disposed in the counter bore and extending into the bore, said holding and retaining member having formed therein a slot fashioned adjacent to its inner end for engagement with a portion of the rod, said slot being positioned to be moved into and out of substantial registry with a portion of the slot through the walls of the carrying block when the latter 35 is rotated about the axis of the holding and retaining member.

- 4. A device of the character described comprising a carrying block provided with a bore and with a counterbore at one end, 45 said carrying block being formed with a slot extending transversely from the outer wall thereof to the bore and longitudinally for the entire length of the block, said slot having a width greater than the diameter of 50 a rod to be engaged, a rotatable holding and retaining member disposed in the counterbore and extending into the bore, said holding and retaining member having formed therein a slot fashioned adjacent to its inner end for engagement with a portion of the rod, said slot being positioned to be moved into and out of substantial registry with a portion of the slot through the walls of the carrying block when the latter is rotated 55 about the axis of the holding and retaining member, and means carried by the carrying block and engaging the holding 60

and retaining member to hold these elements in adjusted relative positions.

5. A device of the character described 65 comprising a carrying block provided with a bore and with a counterbore at one end, said carrying block being formed with a slot extending transversely from the outer wall thereof to the bore and longitudinally for 70 the entire length of the block, said slot having a width greater than the diameter of a rod to be engaged, a rotatable holding and retaining member disposed in the counterbore and extending into the bore, said holding and retaining member having formed 75 therein a slot fashioned adjacent to its inner end for engagement with a portion of the rod, said slot being positioned to be moved into and out of substantial registry with a portion of the slot through the walls of the carrying block when the latter is rotated about the axis of the holding and retaining member, said holding and retaining member being provided with a plurality of spaced apart transverse bores, and a spring pressed 80 locking plunger carried by said carrying block and normally urged into engagement with said transverse bores selectively to lock said carrying block and said holding and retaining member in adjusted relative positions.

6. A device of the character described 85 comprising a carrying block provided with a bore and with a counterbore at one end, said carrying block being formed with a slot extending transversely from the outer wall thereof to the bore and longitudinally for the entire length of the block, said slot having a width greater than the diameter of a rod to be engaged, a rotatable holding and retaining member disposed in the counterbore and extending into the bore, said holding and retaining member having formed 90 therein a slot fashioned adjacent to its inner end for engagement with a portion of the rod, said slot being positioned to be moved into and out of substantial registry with a portion of the slot through the walls of the carrying block when the latter is rotated about the axis of the holding and retaining member, said holding and retaining member being provided with a plurality of spaced apart transverse bores, a spring pressed locking plunger carried by said carrying block and normally urged into engagement with said transverse bores selectively to lock said carrying block and said holding and retaining member in adjusted positions, and means associated with said plunger and operable at will for causing said plunger to disengage said bores.
